UNITED STATES PATENT OFFICE.

RUSSELL A. TONKS, OF SOUTH ORANGE, NEW JERSEY, ASSIGNOR TO TONKS BROTHERS CO., OF NEWARK, NEW JERSEY.

DESIGN FOR A BABY'S TOOTH CUTTER.

Application filed December 31, 1926. Serial No. 20,248. Term of patent 3½ years.

To all whom it may concern:

Be it known that I, RUSSELL A. TONKS, a citizen of the United States, residing at South Orange, in the county of Essex and State of New Jersey, have invented a new, original, and ornamental Design for Baby's Tooth Cutter, of which the following is a specification, reference being had to the accompanying drawing, forming part thereof.

I claim:

The ornamental design for a baby's tooth cutter as shown.

RUSSELL A. TONKS.
